UNITED STATES PATENT OFFICE.

HENRY THAU, OF NEW YORK, N. Y.

MAGNETO CALL.

SPECIFICATION forming part of Letters Patent No. 290,495, dated December 18, 1882.

Application filed March 17, 1883. (No model.)

To all whom it may concern:

Be it known that I, HENRY THAU, of the city, county, and State of New York, have invented a new and Improved Magneto Call, of 5 which the following is a full, clear, and exact description.

My invention relates to the class of call-signals in which magneto-electric machines are employed to generate a current for ringing bells to make signals at distant points; and 10 it consists in a series of knobs or lever-pulls provided with spring-contacts, which close the circuit leading to the bell on the particular floor or at the room or station to be signaled 15 when the magneto-electric machine begins to be rotated by drawing the knob or pull.

In the accompanying drawings, Figure 1 is a rear elevation, and Fig. 2 is a side elevation, showing my improvement applied to an ordinary straight door-pull. Figs. 3 and 4 show 20 the improvement applied to a lever-pull. Fig. 5 shows the electrical connections with the different signal-bells.

Identical parts in the different figures are 25 represented by the same letters of reference.

The magneto-electric machine A is of the usual well-known description, consisting of the permanent U-magnets a, having pole-pieces d, between which revolves a Siemens 30 bipolar armature, c, having one terminal of its wire connected with the armature-shaft, while the other terminal communicates with an insulated pin, d', extending through one of the journals of the armature.

Supported on the magneto-electric machine 35 A, Figs. 1 and 2, by two arms, e, there is a shaft, B, carrying at one end a toothed sector, C, which engages the pinion f on the shaft of the armature c, and on each end of the shaft 40 B there is an arm, g. A rod, h, extends through the arm g, and is engaged by hooks i, jointed to the rods j, attached to the pull-knobs k. The hooks i are pressed down into engagement with the rod h by springs l, attached to the rods j. 45 A notch, m, terminating in an incline, n, is formed in the rod j, and above the rod j are supported two contact-springs, o p, by the insulating-block r. To the lower spring, p, is secured a block, q, of insulating material, 50 which rests in the notch m in the rod j. Nor-

mally, the contact-springs o p are not in contact with each other.

Referring more particularly to Fig. 5, the circuit is from the ground-wire s, spring t, pin d', wire of the armature c, and frame of the 55 magneto-electric machine, wire u, contact-spring p, spring o, and wire r, to a distant bell, 1 or 2, having one of its terminals grounded.

The principal use of this call is for door-bells in flats and tenement-houses. There will be as many pull-knobs k as there are suites of apartments; but only one magneto-electric machine will be needed for any number of floors or apartments. The knob belonging to 60 any apartment controls the wire leading to that apartment, and when it is pulled completes the circuit from the magneto-electric machine to that apartment by the engagement of the inclined surface n with the block q on the spring 65 p. This raises the spring p and brings it into contact with the spring o, where it remains during the outward and inward movement of the rod j, and until the insulating-block q drops into the notch m. The knob k is pulled outward against the pressure of the spring D on the shaft B, which returns the parts to their 70 normal position when the knob is released. The outward movement of the knob swings the toothed sector C, which revolves the armature c of the magneto-electric machine, thus creating a current which rings the bell on the 75 wire connected with the contact-spring o. The retractive movement of the parts also generates a current, which causes the bell to ring. 80

In the call shown in Figs. 3 and 4 a shaft, B', carries at one end a toothed sector, C, held in its normal position by a spring, D'. This sector C engages the pinion f of the magneto-electric machine. Several lever-pulls E are 85 placed loosely on the shaft B', and are notched in the side of their bosses to receive the pins w, projecting from the shaft B'. The notches in the bosses of the levers are of sufficient width to permit one of the levers to turn the 90 shaft without moving the other levers, the levers not depressed being held in an elevated position by springs a'. Each lever E carries a cam, b', of insulating material capable of 95 raising the lower contact-spring, p, and com- 100

pleting the electrical circuit whenever the lever is depressed. At the same time the sector C turns the armature of the magneto-electric machine and the current passes to the bell at the distant point.

What I claim is—

1. The combination of two or more pulls and a corresponding number of pairs of electrical contact points with a magneto-electrical apparatus, a series of alarms, and wires suitably connected to establish the necessary circuits, substantially as shown and described.

2. In a magneto-electric call, a pull having an inclined or beveled shoulder for operating contact-springs, the toothed sector and magneto-electric machine, in combination with the circuit-wires and contact-springs, arranged as shown and described, to operate as specified.

HENRY THAU.
